UNITED STATES PATENT OFFICE

HANS CHRISTIAN JORGENSEN, OF MONTREAL, QUEBEC, CANADA

FURNACE

Application filed October 11, 1928. Serial No. 311,918.

My invention relates to improvements in furnaces, and the object of the invention is to devise a furnace in which a maximum amount of combustion takes place and a maximum amount of heat absorbed and utilized by the furnace for heating purposes so that such heat will not be lost by passing to the stack, in which the heat absorbing surfaces of the walls is increased to a maximum, and in which the incandescent fuel of the fire bed is brought into direct contact with the absorbing surfaces of the walls, and it consists essentially of the arrangement and construction of parts as hereinafter more particularly explained.

Fig. 1 is a sectional perspective view of my furnace, the front portion being removed, one wall of the furnace being broken away intermediate of its height to exhibit the interior construction thereof.

Fig. 2 is a sectional plan view of my furnace.

Fig. 3 is a longitudinal sectional view through Fig. 2, intermediately broken away of its length.

In the drawings like characters of reference indicate corresponding parts in each figure.

1 indicates the base of a furnace forming an ash pit.

The body of the furnace comprises a front section 2, a rear section 3, and a series of intermediate sections 4. The front section 1 is hollow and provided with a fire door opening 5 and a flue opening 6. The interior of the section 2 is utilized as water space, such water being supplied through the pipes 2^x and carried off by the outflow pipe 2° located at the top of the section. The rear section 3 is also hollow to form a water space. The inner wall is formed into a series of cylindrical air flues 3^x between which are formed inwardly extending hollow ribs 3° which are substantially arrow shaped in form so as to provide a maximum of heat absorbing surface on each side of each rib.

The intermediate sections 4 are also hollow, the side wall of each intermediate section being provided with semi-cylindrical chan-

cal channel of the next adjacent section form cylindrical air flues extending vertically at each side of the furnace.

Between the flues are formed hollow ribs 6 which are also arrow shaped in form so as to provide a maximum heat absorbing surface on each side of each rib.

The upper end of all the sections are arched in form as indicated at 7 and the ribs 6 arched around, this portion of the rib being of greater area so as to provide greater heat absorbing surface at the top of the furnace so as to absorb a maximum amount of heat as it passes to the stack.

By this arrangement it will be seen that a fire pot is formed between the inwardly extending vertical ribs 6 providing V-shaped spaces between each pair of ribs into which the fire bed enters, the upper portion of the arch above the fire bed level forming a combustion chamber.

8 and 9 are the grate members of the furnace which are pivotally mounted as indicated at 10 and 11. Between the grate members 8 and 9 I extend a pipe 12 which is utilized to heat water for domestic purposes.

13 is a preheating chamber, the bottom of which is provided with perforations 13^x and with an end door in the furnace front. 14 is a slide plate suitably operated by a handle 15 and is also perforated as indicated at 14^x, such perforations being moved into a more or less registering position with the perforations 13^x so as to control the supply of air passing into the preheating chamber. The hot air in the ash pit 1 utilized to supply the preheating chambers, such air passing upward through the cylindrical flues 3^x and 4^x to mix with the gases given off from the fire bed.

The sections 4 are interconnected together by a series of nipples 15 so as to form a continuous water space within all the sections of the furnace.

On each side of the fire pot slightly above the bottom of the furnace door opening 10 I provide curtain walls 16 and 17 supporting a movable baffle plate 18 upon ribs 16^x and 17^x.

The curtain walls 16 and 17 are supported,

as indicated at 17°, by means of bolts extending through the lugs formed integral with the body of the furnace into the curtain walls.

When it is desired to feed the furnace with ⁵ fresh fuel the plate 18 is drawn out through the furnace door opening.

The curtain walls 16 and 17 are suitably secured to the inwardly extending ribs 6 and together with the plate 18 serve to direct the ¹⁰ hot gases rising from the fire bed laterally to each side thereof and into the interspaces between the ribs 6 and into the cylindrical flues 4^x where they mix with the upward flow of hot air from the preheating chambers, ¹⁵ thereby forming a combustible mixture which is ignited by the heat radiating from the hot fire bed.

By this means the fuel at the sides of the fire bed is ignited and burnt so that the heat ²⁰ thereof is in direct contact with the furnace walls to be absorbed thereby.

The sections 2, 3 and 4 are secured together by suitably located bolts 19 and 20.

21 is an outlet flue leading through the ²⁵ upper portion of the ribs 6 and provided with a series of orifices 22 through which the products of combustion pass so as to be carried up the flue through the chimney stack. ³⁰ The flue 21 leads at its front end through the ribs 6 to the opening 6° provided with a suitable door 6^x.

A cross wall 23 may be inserted at its ends in any pair of opposing interspaces between the ribs 6 so as to limit the fire space to any ³⁵ size desired in accordance with the season of the year.

It will be readily seen by locating the pre-heating chambers in the ash pit the heat of the ⁴⁰ air contained in the ash pit which would otherwise be lost is utilized for heating the air to supply the flues 4^x. The amount of air so supplied is controlled to suit all temperatures and all kinds of fuel by means of the ⁴⁵ slide plate 14, the perforations 14^x of which are brought more or less into registering position with the perforations 13, thus controlling the amount of air passing therethrough.

By the combined use of my curtain wall, ⁵⁰ preheating air chambers, hot air flues, and means for regulating the air therethrough, an economic combustion of the gases is assured and the heat distributed in such a way as to be most effective.

From this description it will be seen that ⁵⁵ I have devised a furnace in which a maximum amount of combustion will take place and a maximum amount of heat absorbed and utilized by the furnace in such a way ⁶⁰ that the heat will not pass to the stack and be lost, and in which the air passing through the fire bed is so directed that the whole fire bed will become incandescent right to the side walls of the furnace, preventing a body of ⁶⁵ dead ash forming at each side of the fire bed,

preventing the full absorption of heat by the furnace walls by shielding such walls.

The hot gases as they are carried laterally mix with the hot air carried up by the vertical flues and complete combustion thereof ⁷⁰ takes place, the gases being fully utilized for the production of heat.

The curtain walls 16 and 17 and plate 18 also act as a baffle to retard the upward flow ⁷⁵ of the gases before passing into the combustion chamber within the curtain walls so that such gases are thoroughly mixed with the hot air rising upward through the flues 4^x, and thereby forming a completely combustible mixture.

It may also be pointed out that by forming my furnace in sections the furnace may be readily manufactured, such sections being standard so that a furnace of any desired size may be built by simply inserting a greater or less number of sections.

What I claim as my invention is:—

In a furnace, a body of inverted U-shaped form forming a central fire pot and combustion chamber thereover, a grate extending across the bottom of the open fire pot, a series of vertical flues formed in the walls of the furnace body at each side of the fire pot, hollow ribs projecting into the fire pot and located between the flues and forming water spaces the interspaces between the ribs communicating with the interior of the flues and with the fire pot and combustion chamber, means for supplying heated air to the lower ends of the flues, a curtain wall located at each side of the fire pot and extending across the open inner side of each interspace above the level of the fire bed and carried by the aforesaid ribs, a removable plate carried between the curtain walls and adapted to be passed outward through the fire door opening and to form directing means whereby the hot gases are directed from the fire bed into the interspaces between the water spaces to pass inward over said curtain walls into the combustion chamber, a preheating air chamber located at the bottom ends of the flues and within the ash pit and so formed as to receive the hot rays from the fire bed on the walls thereof, and having a perforated bottom and a slide damper provided with perforations to control the size of the opening formed by the perforations of the preheating chamber.

HANS CHRISTIAN JORGENSEN.
